US00D978954S

(12) **United States Design Patent** (10) Patent No.: **US D978,954 S**
(45) Date of Patent: **** Feb. 21, 2023**

(54) **VEHICLE CAMERA**

(71) Applicants: **Hyundai Motor Company**, Seoul (KR); **Kia Corporation**, Seoul (KR)

(72) Inventors: **Heung Sun Bong**, Seoul (KR); **Hyun Ho Cho**, Seoul (KR)

(73) Assignees: **Kia Corporation**, Seoul (KR); **Hyundai Motor Company**, Seoul (KR)

(**) Term: **15 Years**

(21) Appl. No.: **35/512,576**

(22) Filed: **Mar. 16, 2021**

(80) **Hague Agreement Data**

Int. Filing Date: **Mar. 16, 2021**

Int. Reg. No.: **DM/213759**

Int. Reg. Date: **Mar. 16, 2021**

Int. Reg. Pub. Date: **Sep. 17, 2021**

(30) **Foreign Application Priority Data**

Jan. 12, 2021 (KR) 30-2021-0001470

(51) LOC (14) Cl. **16-05**

(52) U.S. Cl.

USPC **D16/242**

(58) **Field of Classification Search**

USPC D16/200, 202-203, 206, 207, 218, 219, D16/237, 239, 242; D12/187

CPC H04N 5/232; G04G 21/02; G06F 1/1686
